DESIGN FOR A LIGHTING FIXTURE

Frederic C. Winkler, Lakewood, and Andrew De Vries, Cleveland, Ohio, assignors to Westinghouse Electric & Manufacturing Company, a corporation of Pennsylvania

Application September 19, 1939, Serial No. 87,284

Term of patent 14 years

To all whom it may concern:

Be it known that we, Frederic C. Winkler and Andrew De Vries, citizens of the United States, residing, respectively, at Lakewood and at Cleveland, in the county of Cuyahoga and State of Ohio, have invented a new, original, and ornamental Design for Lighting Fixtures, of which the following is a specification, reference being had to the accompanying drawing, forming a part thereof.

The single figure is a perspective view of a lighting fixture embodying our new design.

We claim:

The ornamental design for a lighting fixture, substantially as shown.

FREDERIC C. WINKLER.
ANDREW DE VRIES.
